UNITED STATES PATENT OFFICE.

WILLIAM L. EWING, OF WHEELING, WEST VIRGINIA, ASSIGNOR TO THE
BUCKEYE GLASS COMPANY, OF MARTIN'S FERRY, OHIO.

DESIGN FOR AN OIL-BURNING LAMP.

SPECIFICATION forming part of Design No. 13,394, dated November 7, 1882.

Application filed September 22, 1882. Term of patent 3½ years.

To all whom it may concern:

Be it known that I, WILLIAM L. EWING, a citizen of the United States, residing at Wheeling, in the county of Ohio and State of West Virginia, have invented and produced a new and original Design for Oil-Burning Lamps, of which the following is a specification, reference being had to the accompanying drawings, forming part thereof.

Figure 1 is a view in perspective of my newly-designed lamp, and Fig. 2 is a view thereof in vertical cross-section.

The leading feature of my design consists in a combined oil-reservoir, base, and handle.

The oil-reservoir A, to which the burner B is attached, rises from the center of a dish-shaped base, C, which is circular in general contour, and which has a handle, D, projecting from its periphery. The said handle is designed to be grasped by the thumb and forefinger, its upper face being provided with a depression, E.

Crystal-colored and multi-colored glass may be used in the fabrication of my newly-designed combined oil-reservoir, base, and handle, and

the contour of the several parts may be slightly altered without detracting from the characteristics obtaining to the design shown in the drawings.

I claim—

1. In an oil-burning lamp, the design herein shown and described for a combined oil-reservoir, base, and handle, said design consisting in an oil-reservoir, a dish-shaped base from the center of which the oil-reservoir rises, and a handle projecting from the periphery of the said base, substantially as described.
2. In an oil-burning lamp, the design herein shown and described for a combined oil-reservoir, base, and handle, said design consisting in an oil-reservoir, a dish-shaped base from the center of which the oil-reservoir rises, said base being circular in general contour, and a handle projecting from the periphery of the base and having a depression in its upper face.

WM. L. EWING.
